No. 838,980.

PATENTED DEC. 18, 1906.

J. W. GRAY.
SAFETY TRIP.
APPLICATION FILED JUNE 14, 1906.

UNITED STATES PATENT OFFICE.

JOSEPH WILLIAM GRAY, OF EVENWOOD, WEST VIRGINIA.

SAFETY-TRIP.

No. 838,980.

Specification of Letters Patent.

Patented Dec. 18, 1906.

Application filed June 14, 1906, Serial No. 321,657.

To all whom it may concern:

Be it known that I, JOSEPH WILLIAM GRAY, a citizen of the United States, and a resident of Evenwood, in the county of Randolph and State of West Virginia, have invented a new and Improved Safety-Trip, of which the following is a full, clear, and exact description.

The invention relates to logging trucks and cars having removable stakes at the sides for holding the logs in position on the truck or car.

The object of the invention is to provide a new and improved safety-trip for holding the stake-chain and the stakes in active position while the truck or car is loaded and en route and to permit the operator to safely release the stake-chain and stakes whenever it is desired to unload.

The invention consists of novel features and parts and combinations of the same, which will be more fully described hereinafter and then pointed out in the claims.

A practical embodiment of the invention is represented in the accompanying drawings, forming a part of this specification, in which similar characters of reference indicate corresponding parts in all the views.

Figure 1 is an end elevation of a portion of a logging-car provided with the improvement. Fig. 2 is a side elevation of the same. Fig. 3 is a transverse section of the seat for the stake, the latter being shown in elevation. Fig. 4 is a sectional side elevation of the improvement on the line 4 4 of Fig. 1. Fig. 5 is an enlarged sectional side elevation of the improvement on the line 5 5 of Fig. 1, and Fig. 6 is a side elevation of the holding and releasing arm for the stake-chain hook.

The logging truck or car A is provided at each side with the usual seats A' for the reception of the shanks B' of the stakes B, employed for holding the logs in position on the truck or car. Each stake B is provided on its outer base with a projection B², on which rests the stake-chain C, fastened with one end link C' on a bolt E and having its other end link C² arranged for engagement with a hook or finger F, mounted to swing on the bolt E as a fulcrum. The free end of the hook or finger F is adapted to be engaged by the eye G' of a holding or releasing arm G, fulcrumed on a bolt H and pivotally connected at its free end with a rod I, extending transversely and provided with an eye I', adapted to engage a catch J for holding the rod I in active position, as indicated in Figs.

1 and 2. The catch J is provided with a locking-handle J' for holding the eye I' against accidental displacement on the catch J, as will be readily understood by reference to Figs. 1 and 5. The bolts E and H are held in the cross-beam of the truck or car A, carrying the corresponding stake B, and the bolts E and H are connected with each other by suitable braces K to strengthen the construction of the device. The catch J is also held in the transverse beam of the truck or car holding the stake B, and when the locking-handle J' of the said catch is swung into a horizontal position, as indicated in dotted lines in Fig. 5, then the eye I' can be readily removed from the catch J or placed in position thereon. Now when the several parts are in the position illustrated in Figs. 1 and 2 then the stake-chain C engages and holds the stake B in position, and the said stake-chain is locked in place by the hook or finger F, which in turn is locked in position by the holding and releasing arm G, held against movement by the lock-rod I.

Now when it is desired to unload the car it is only necessary for the operator standing on the side of the car opposite the one on which the unloading is to be done to first swing the handle J' in a horizontal position, then disengage the eye I' from the catch J and pull the rod I inward toward himself to swing the holding and releasing arm G out of engagement with the hook or finger F. Now the pressure exerted by the logs against the inner face of the stake B causes the latter to swing outward and downward, (see dotted lines in Fig. 1,) and in doing so the said stake B pulls on the chain C and draws the link C² thereof out of engagement with the released hook or finger F. Thus the stake-chain C is released and the stake B is free to fall, so that the logs can be readily discharged over the side of the logging truck or car.

From the foregoing it will be seen that by the arrangement described the operator is not at any time in danger of being struck by the logs when releasing the stakes, and the device permits of securely holding the stakes in position, and enables the operator to readily release the same, as above explained.

Having thus described my invention, I claim as new and desire to secure by Letters Patent—

1. A safety-trip for logging trucks and cars, provided with a swing-hook for engagement with one end of the stake-chain, and a holding

and releasing arm mounted to swing and adapted to engage the said swing-hook.

2. A safety-trip for logging trucks and cars, comprising a stake, a stake-chain fastened at one end and adapted to engage the said stake, a swing-hook adapted to engage the other end of the said stake-chain, and a manually-controlled holding and releasing device mounted to swing and having an eye for engaging the said swing-hook.

3. A safety-trip for logging trucks and cars, comprising a stake, a stake-chain fastened at one end and adapted to engage the said stake, a swing-hook adapted to engage a link of the said stake-chain, a holding and releasing arm mounted to swing and engaging the said swing-hook, and manually-controlled means for manipulating the said arm.

4. A safety-trip for logging trucks and cars, comprising a stake, a stake-chain fastened at one end and adapted to engage the said stake, a swing-hook adapted to engage a link of the said stake-chain, a holding and releasing arm mounted to swing and engaging the said

swing-hook, a rod connected with the said arm, and a safety-catch for normally holding the said rod in position.

5. A safety-trip for logging trucks and cars, comprising a stake having a projection on its outer face, a stake-chain adapted to rest on said projection, a fixed bolt, the said stake-chain being fastened at one end to one end of said bolt, a hook or finger mounted to swing on the other end of said bolt and adapted to engage the other end of said stake-chain, a holding or releasing arm mounted to swing and having an eye for engaging the free end of the said hook or finger, a rod pivotally connected with said arm, and means for holding the rod in active position.

In testimony whereof I have signed my name to this specification in the presence of two subscribing witnesses.

JOSEPH WILLIAM GRAY.
